ELECTRIC SHAVER

Bernard Tissot-Dupont, Annecy (Haute-Savoie), France

Application April 8, 1952, Serial No. 281,095

Claims priority, application France October 15, 1951

6 Claims. (Cl. 30—34)

This invention relates to a dry shaver of the type comprising a series of cutting members or blades which are reciprocated back and forth and co-operate with the inner face of a perforated guard plate, said cutting members being driven from a blade carrier or cutting head supported and guided by means of an oscillating lever.

One object of the invention is to provide shaver with a shearing device adapted to cut long hair, while it has been impossible until now to do so with the aid of the perforated guard plate.

Another object is to provide for the possibility of quick replacement of the guard plate of very simple manufacture and relatively high strength.

A further object of the invention is to eliminate the risks of deterioration due to the friction of the blade carrier against the usual slide-bars or to the friction of the blades against the inner face of the perforated guard plate in the event that the latter be deformed under the action of an excessive pressure against prominences of the face, such as the chin, for example.

Other objects and features of the invention will be apparent from the following detailed description with reference to the accompanying drawings in which:

Figure 1 is a plan view of the guard plate,

Figure 2 is a sectional view of said guard plate prior to the mounting operation,

Figure 3 shows the guard plate in operative position,

Figure 4 is an enlarged view of the whole shaver, partly in section,

Figure 5 illustrates a detail of mounting of the blade,

Figure 6 is a front view of the depilating device,

Figure 7 is a sectional side view of the said device.

The guard-plate 1 is made of a hard spring metal of about one tenth of a millimeter in thickness, and throughout the area delimited by dotted lines (Fig. 1), it has a great number of perforations or openings of about 0.5 mm. in diameter and a centre to centre distance of more or less one millimeter.

On both longitudinal sides of the rectangular strip constituting the guard-plate, the marginal portions have a profile such as shown in Fig. 2 and are upturned through an angle α .

Fig. 3 shows the guard-plate 1 inserted in slots of supports 2 and 3. The distance between the supports 2 and 3 is adjusted in such a manner that the guard-plate 1 may be flexed to a semi-cylindrical form, the axis of which passes through point O and the periphery of which corresponds to a circular sector equal to 2α . Thus, the guide-slots for the guard-plate may be machined at right angles with respect to the inner surface of supports 2 and 3. Another advantage of the profile represented in Fig. 2 is the fact that the perforated portion of the guard-plate is completely kept apart from the supports 2 and 3.

In the general disposition of the shaver shown in Fig. 4, the carrier carries four blades, the details of mounting being represented in Fig. 5. Each of the blades 4 is guided within two vertical grooves united at their upper end by a horizontal groove. Each blade 4 is submitted to a vertical thrust exerted from bottom to top by a pin 7 loaded by spring 6. The blade carrier 5 is cut out with a central aperture through which the upper portion of the oscillating lever 8 is introduced. At its upper end, the lever 8 carries a damping roller 9 made of rubber or a similar material and having a diameter equal to the distance between the two adjacent blade holding members.

The carrier 5 rests resiliently on a shoulder of the oscillating lever 8 with the interposition of the spring 11 and of the convex washer 10. The latter has a profile substantially concentric with the oscillation axle 12 so as to enable the blade-carrier 5 to take oblique positions with respect to the lever 8 without the contribution of the spring 11. As a result of this particularity, the blade carrier 5 may remain horizontal, whilst the lever 8 oscillates with an amplitude of sufficient value amounting to more or less 30 degrees, without any other guiding but the pressure of the blades against the guard-plate, said pressure being actually necessary to obtain the result considered, that is to say to shear-off the hair passing through the perforations.

15 The mounting of the blades such as described above will enable said blades, on the one hand, to follow the movements of the carrier, and on the other hand, to bear continually and independently from each other against the inner face of the guard-plate by means of an individual spring for every blade.

20 This kind of mounting ensures the advantage consisting on the one hand in the fact that each of the blades may be always placed in the best conditions of cutting while limiting the pressure against the guard-plate and, 25 on the other hand, in the fact that the blades may move back without any risk of deterioration for the guard-plate or for the blades in the event that the user should produce a momentary deformation of the guard-plate by exerting an excessive pressure against certain areas of the face, such as the chin for example.

30 The carrier together with its blades is reciprocated by a rectilinear movement at a frequency reaching about 100 strokes per second. In order to obtain the maximum efficiency, the amplitude of the movement should be at least equal to the distance separating two consecutive blades from each other.

35 The spring 11 is designed so as to balance the combined thrust of all the springs 6. As the blade carrier is made of light metal, the weight of the carrier together with its blades is unimportant in comparison with the strength of the springs 6, as may be stated by a satisfying working in any position.

40 The depilating device of the shearing type (Figs. 6 and 7) is composed of a fixed rectilinear comb 13 comprising a certain number of teeth, of a cutter 14 comprising also a certain number of teeth, the width of these teeth being superior to the interval between two teeth of the comb 13, whereas the interval between two teeth of the cutter 14 is smaller or equal to the amplitude of oscillation imparted to said cutter.

45 The cutter 14 is continuously pressed against the inner face of the teeth of comb 13 under the action of two springs 15. The back and forth motion is produced by means of the crank-pin 16 rigid with the part 17 mounted oscillating with the shaft 12, said crank-pin being engaged with the fork formed at the lower side of cutter 14.

50 Of course, any modifications of the embodiments hereinbefore described may be performed within the scope and spirit of the present invention. Thus, for example, the number of the blades supported by the carrier may be increased and the blades may be placed with a certain obliquity so as not to be quite perpendicular to the plane of oscillation of the lever 6.

55 What I claim is:

1. A cutting device, comprising in combination, an elongated housing open at one end; a perforated plate member mounted on said housing covering the open end thereof; a lever member mounted in said housing for oscillation about an axis normal to the axis of said housing; a support member having a base portion extending substantially parallel to said plate member and mounted on the end of said oscillating lever member for movement thereby; cutter means resiliently mounted on said support member extending toward said plate member and in yieldable contact with the inner surface of said plate member; and a bearing member mounted on said lever member between said support member and the axis of oscillation of said lever member and having a curved surface bearing against the base portion of said support member, the center of said curved surface lying in

the axis of oscillation of said lever member, whereby during oscillation of said lever member said support member is reciprocated along a line substantially parallel with said plate member and at a uniform distance therefrom.

2. A cutting device, comprising in combination, an elongated housing open at one end; a perforated plate member mounted on said housing covering the open end thereof; a lever member mounted in said housing for oscillating about an axis normal to the axis of said housing; a support member having a base portion extending substantially parallel to said plate member and mounted on the end of said oscillating lever member for movement thereby; cutter means resiliently mounted on said support member extending toward said plate member and in yieldable contact with the inner surface of said plate member; a bearing member mounted on said lever member between said support member and the axis of oscillation of said lever member and having a curved surface bearing against the base portion of said support member, the center of said curved surface lying in the axis of oscillation of said lever member; and resilient means on said lever member permanently urging said bearing member against said base portion of said support member, whereby during oscillation of said lever member said support member is reciprocated along a line substantially parallel with said plate member and at a uniform distance therefrom.

3. A cutting device, comprising in combination, an elongated housing open at one end; a perforated plate member mounted on said housing covering the open end thereof; a lever member mounted in said housing for oscillation about an axis normal to the axis of said housing; a support member having a base portion extending substantially parallel to said plate member and mounted on the end of said oscillating lever member for movement thereby; cutter means resiliently mounted on said support member extending toward said plate member and in yieldable contact with the inner surface of said plate member; a bearing member mounted on said lever member between said support member and the axis of oscillation of said lever member and having a curved surface bearing against the base portion of said support member, the center of said curved surface lying in the axis of oscillation of said lever member, whereby during oscillation of said lever member said support member is reciprocated along a line substantially parallel with said plate member and at a uniform distance therefrom; comb means having a plurality of comb elements arranged on the outer surface of said housing along said perforated plate member; a cutting member having a plurality of blade portions fewer than the number of said comb elements in contact with said comb elements and operatively connected to said oscillating lever member for movement thereby so that said blade portions are reciprocated along said comb elements; and resilient means secured to the outer surface of said housing permanently urging said cutting member into contact with said comb means.

4. A cutting device, comprising in combination, an elongated housing open at one end; a perforated plate member mounted on said housing covering the open end thereof; a lever member mounted in said housing for oscillation about an axis normal to the axis of said housing; a support member having a base portion extending substantially parallel to said plate member and mounted on the end of said oscillating lever member for movement thereby, and having a plurality of blade holding portions projecting from said base portion toward said

plate member; a plurality of blade members carried by said support member, each blade member being mounted in one of said blade holding portions thereof, extending toward and being resiliently urged into yieldable contact with the inner surface of said plate member; and a bearing member mounted on said lever member between said support member and the axis of oscillation of said lever member and having a curved surface bearing against the base portion of said support member, the center of said curved surface lying in the axis of oscillation of said lever member, whereby during oscillation of said lever member said support member is reciprocated along a line substantially parallel with said plate member and at a uniform distance therefrom.

5. A cutting device, comprising in combination, an elongated housing open at one end; a perforated plate member mounted on said housing covering the open end thereof; a lever member mounted in said housing for oscillation about an axis normal to the axis of said housing; a support member having a base portion extending substantially parallel to said plate member and mounted on the end of said oscillating lever member for movement thereby, and having a plurality of blade holding portions projecting from said base portion toward said plate member; a plurality of blade members carried by said support member, each blade member being mounted in one of said blade holding portions thereof, extending toward and being resiliently urged into yieldable contact with the inner surface of said plate member; a bearing member mounted on said lever member between said support member and the axis of oscillation of said lever member and having a curved surface bearing against the base portion of said support member, the center of said curved surface lying in the axis of oscillation of said lever member; and resilient means on said lever member permanently urging said bearing member against said base portion of said support member, whereby during oscillation of said lever member said support member is reciprocated along a line substantially parallel with said plate member and at a uniform distance therefrom.

6. A cutting device, comprising in combination, an elongated housing open at one end; a perforated plate member mounted on said housing covering the open end thereof; a lever member mounted in said housing for oscillation about an axis normal to the axis of said housing; an elongated support member having a base portion extending substantially parallel to said plate member and mounted substantially midway between its ends on the end of said oscillating lever member for movement thereby; a plurality of cutter members resiliently mounted on said support member extending toward said plate member and in yieldable contact with the inner surface of said plate member; and a bearing member mounted on said lever member between said support member and the axis of oscillation of said lever member and having a curved surface bearing against the base portion of said support member, the center of said curved surface lying in the axis of oscillation of said lever member, whereby during oscillation of said lever member said support member is reciprocated along a line substantially parallel with said plate member and at a uniform distance therefrom.
